Primary Examiner — Jae Liang*Assistant Examiner* — Adedoyin Taiwo Odeyale(74) Attorney, Agent, or Firm — McGarry Bair PC(57) CLAIM

The ornamental design for a ceiling fan as shown and described.

DESCRIPTION

FIG. 1 is a top perspective view of a first embodiment of a ceiling fan, showing my new design.

FIG. 2 is a bottom perspective view of the first embodiment.

FIG. 3 is a top view of the first embodiment.

FIG. 4 is a bottom view of the first embodiment.

FIG. 5 is a front view of the first embodiment.

FIG. 6 is a rear view of the first embodiment.

FIG. 7 is a right-side view of the first embodiment; and,

FIG. 8 is a left-side view of the first embodiment.
